UNITED STATES PATENT OFFICE.

ALEXANDER E. CROUSE AND FRANK B. ORTON, OF WOODS COUNTY,
OKLAHOMA TERRITORY.

EVENER AND DOUBLETREE CARRIER.

No. 838,847.

Specification of Letters Patent

Patented Dec. 18, 1906.

Application filed August 9, 1906. Serial No. 329,962.

To all whom it may concern:

Be it known that we, ALEXANDER E. CROUSE and FRANK B. ORTON, citizens of the United States, residing in Woods county, 5 Oklahoma Territory, (whose post-office address is Kiowa, Kansas,) have invented certain new and useful Improvements in Evener and Doubletree Carriers, of which the following is a description, reference being had to the accompanying drawings and to the figures of reference marked thereon.

The object of this invention is to provide an adjustable lever mechanism for plows, drags, and other agricultural implements by means 15 of which eveners and swingle and double tree carriers to which teams are attached, with or without a pole, may be raised to keep the eveners, trees, and traces from interfering with the horses when the traces are slack in 20 turning and backing.

Referring to the accompanying drawings, in which similar figures of reference indicate like parts, Figure 1 is a view in perspective of a wheel-plow, showing the invention applied 25 thereto. Fig. 2 is a view in perspective of the lever mechanism detached; and Figs. 3, 4, and 5 are detail views of detached parts thereof.

1 indicates a wheeled plow, to which the invention is applied as follows: To the operating-handle lever 2 of the plow, pivoted to the frame 3, is connected by a strap or clamp 4, one end of a rod pivoted thereto, the other end of which is adjustably and pivotally connected by bolt-holes 6 and bolt 7 with the upper end of a lever-arm 8, having bolt-holes 9. The lower end of the lever-arm 8 terminates in a web or plate 10, formed with the rings or bearings 11 for a pin or shaft 12, coupling it 35 to the frame 3 at its forward end. The web or plate 10 has formed with it a forwardly-extending curved arm 13, which constitutes, with the web or plate 10 and lever-arm 8, a bell-crank lever, the whole preferably cast in 40 one piece. While the bell-crank lever is formed with the plate 10, the connection or joint between the lever-arm 8 and arm 13 45 may be of other suitable construction.

The forward end of the curved arm 13, which 50 may be termed the "clamp-arm," terminates in a slotted portion 14, having at its outer end a circular opening 15, in which is mounted a ring 16 with holes 17, engaging pins 18 in the arm 13, thereby permitting the ring 16 to

oscillate. Through the ring 16 projects the 55 upper end of the evener-post 19, held in place from pulling off by a split lug-pin 20, inserted in the upper end of post 19. The lower portion of post 19 is formed with two spreading-arms 21, terminating in hooks 22, which 60 engage the eyebolts 23, passing through and secured to the evener 24 by nuts 25.

By means of the foregoing-described arrangement of parts and levers on pulling back the handle-lever 2 or releasing it the 65 evener 24, carrying the trees, may be raised or lowered through the intervening rod 5, the bell-crank lever, and the evener-post. The upper end of the evener-post, playing freely in the oscillating ring at the end of the 70 clamp-arm 13, is adapted to accommodate itself to the uneven movements of the wheeled plow when the horses are moving over uneven ground by either rising and falling or oscillating with the ring 16 in the end of arm 13. 75 In lieu of the specified joint between the arm 13 and the evener-post 19 any other form of joint may be used which will permit of the same movements described of the evener-post. By means of this invention the evener 80 is held high off the ground in turning at the end of the field, thereby preventing the horses from getting their legs over the traces and getting unhitched. By means of the connection of the evener-post with the clamp-arm 85 13 the evener-post can have the required play to adapt it to rough and hilly country.

Having described the invention, we claim—

1. An adjustable lever mechanism for eveners and swingle and double tree carriers of agricultural implements, which consists of an evener-post carried by the evener, a bell-crank lever connected to the post, a handle-lever, and a rod connecting the handle-lever with the bell-crank lever, as herein set forth. 95

2. An adjustable lever mechanism for eveners and swingle and double tree carriers of agricultural implements, which consists in an evener-post having a forked lower end with hooks engaging eyebolts on the evener, a bell-crank lever having a curved clamp-arm with an oscillating ring in its forward end through which loosely projects the upper end of the evener-post, a lever-handle arm, and a rod connecting the lever-handle arm with the bell-crank lever, as herein set forth. 105

3. An adjustable lever mechanism for eveners of agricultural implements, which con-

- sists in an evener-post carried by and having a loose jointed connection at its lower end with an evener, a bell-crank lever having a curved clamp-arm connected with the evener-post by a joint permitting a vertical and oscillating play of the evener-post, a lever-handle arm, and a rod connecting the lever-handle with the bell-crank lever, as herein set forth.
- 10 4. An adjustable lever mechanism for eveners of agricultural implements, which consists in an evener-post carried by and having a loose-jointed connection at its lower end with an evener, a bell-crank lever cast in one piece and having a plate or web with a clamp-arm projecting from one side thereof and a vertical lever-arm projecting from the other side thereof, the clamp-arm having a jointed and sliding connection with the evener-post, whereby the latter can move vertically and oscillate thereon, a handle-lever, and a rod connecting said lever with the vertical arm of the bell-crank lever as herein set forth.
- 15 5. An adjustable lever mechanism for eveners of agricultural implements, which consists in a handle-lever, an evener-post carried by the evener, and a lever mechanism con-

necting the handle-lever with the evener-post, as herein set forth.

6. An adjustable lever mechanism for eveners of agricultural implements, comprising an implement, an operating-lever therefor, an evener, an evener-post carried thereby, a bell-crank lever having one of its arms in engagement with said evener-post, and an operating member connecting said operating-lever and the other arm of said bell-crank lever.

7. An adjustable lever mechanism for eveners of agricultural implements, comprising an implement, an operating-lever therefor, an evener, an evener-post carried thereby, a bell-crank lever, one arm of which has a sliding connection with said evener-post and an operating member connecting said operating-lever and the other arm of said bell-crank lever.

In testimony whereof we affix our signatures in presence of two witnesses.

ALEXANDER E. CROUSE.
FRANK B. ORTON.
